(57) **CLAIM**

The ornamental design for a sheet with camouflage pattern, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a top plan view of a first embodiment of a sheet with camouflage pattern; and,

FIG. 2 is a top plan view of a second embodiment of sheet with camouflage pattern.

The broken lines surrounding the drawings depict the boundaries of the claim and form no part thereof.

**1 Claim, 2 Drawing Sheets
(2 of 2 Drawing Sheet(s) Filed in Color)**
